UNITED STATES PATENT OFFICE.

RICHARD G. WILLIS, OF MARION, ALABAMA.

DOOR LATCH.

Application filed July 16, 1921. Serial No. 485,204.

To all whom it may concern:

Be it known that I, RICHARD GRANGER WILLIS, a citizen of the United States, and a resident of Marion, in the county of Perry 5 and State of Alabama, have invented certain new and useful Improvements in Door Latches, of which the following is a specification.

This invention relates to latches especially 10 adapted for application to doors.

An important object of this invention is to provide a door latch having a pivotal latch member which may be conveniently operated from either side of the door and 15 which is provided with a housing for preventing cattle, horses and all stock from operating the latch through contact with the same.

The invention forming the subject matter 20 of this application also aims to provide a door latch having a hood which protects the latch plate and keeper from snow and ice which frequently renders a door latch inoperative.

25 A further object is to provide a door latch which may be applied to a door without the necessity of mutilating the door so that should it become necessary to remove the latch permanently, the door will not have 30 to be repaired.

A still further object is to provide a door latch of a highly simplified construction, efficient in use and extremely cheap to manufacture.

35 Other objects and advantages of the invention will be apparent during the course of the following description.

In the accompanying drawing forming a part of this application and in which like 40 numerals are employed to designate like parts throughout the same,

Figure 1 is an elevation of the improved latch applied.

Figure 2 is a vertical sectional view 45 through the improved latch.

Figure 3 is an end elevation of the improved latch applied.

Figure 4 is a vertical transverse sectional view taken on line 4-4 of Figure 2.

50 In the drawings, wherein for the purpose of illustration is shown a preferred embodiment of the invention, the numeral 5 designates a door frame in which a door 6 is supported by means of hinges 7.

55 The improved latch is preferably formed entirely of sheet metal and includes a flat

metallic base 10 formed from a length of sheet metal bent intermediate its ends to form a transversely curved shield or hood 11. The edge portions of the hood 11 are 60 bent so as to lie in contact with the edge portions of the base 10 thereby forming a pair of attaching flanges 12 which receive fastening devices 13 in the nature of screws. 65

The base 10 which is of elongated formation is provided along one end with a transverse incision which forms a partly severed portion 14 which is bent back upon the base to form a guide or extension 16 on the forward end of a latch plate designated by the 70 numeral 18.

As illustrated in Figure 3, the partly severed portion 14 which cooperates with the adjacent portion of the base forming the guide is bent upon itself and in contact with 75 the hood 11 as indicated at 20. If desired, the terminal of the partly severed portion 14 may be riveted, soldered or otherwise secured to the hood.

The latch plate 18 which is preferably 80 formed from flat metal has its rear end portion formed with a longitudinal incision 22 which provides a shank 23 and a flange 24 which extends outwardly at right angles to the plate to constitute a manipulating element. The shank 23 is supported by means of a bolt 26 extended through the base plate and a door 6. The portion of the bolt 26 which is extended through the door is screw threaded and is provided with a handle 27 90 held securely on the bolt by means of a pair of lock nuts 28. The bolt 26 is non-rotatably connected to the latch plate by means of outwardly directed lugs 29 which engage the head of the bolt. By reason of this construction, the rotation of the handle 27 will 95 result in rotation of the bolt 26 for elevating the latch plate.

The base plate 10 is provided with a second partly severed portion 30 which is bent 100 back upon the plate to form a guide stop element for limiting downward movement of the latch plate.

The partly severed portion 14 which is bent back upon the base plate defines an 105 opening within which is arranged a keeper 33. The keeper is preferably formed from a single length of metal having its ends secured to the door frame and its intermediate portion bent to form a retaining means for 110 a tongue 34 extended from the forward end of the latch.

In applying the improved door latch, the base plate is screwed onto the door so that one end of the base plate will extend over the door frame. The keeper 33 is now 5 cured to the door frame within the openings defined by the partly severed portion 14 so that the keeper as well as the other parts of the device will be protected from snow, etc.

The improved latch may be operated from 10 one side of the door by means of the operating handle 27 and from the other side of the door by means of outwardly directed flange 24. The hood 11 is adapted to be manually gripped simultaneously with the engagement 15 of the fingers with the flange 24 so that as the latch plate is elevated, the door may be pulled open. It is thus apparent that the hood 11 in addition to protecting the latch plate constitutes a gripping device or handle 20 for the door.

The hood 11 which extends over the latch plate and keeper are to prevent live stock from contacting with the latch plate and thereby operating the same. The device is 25 preferably painted white so that the same may be seen at night.

Having thus described the invention, what is claimed is:—

1. A door latch formed from a blank of 30 flat metal having an attaching shank and a flange which is bent outwardly to form a manipulating element, a keeper associated with the latch plate, and a base having an integral hood extending over said blank of metal whereby to protect the same from 35 engagement by cattle, the ends of the hood being open for the reception of the fingers of the operator.

2. A door latch formed from a blank of 40 flat metal having an attaching shank and a flange which is bent outwardly to form a manipulating element, a keeper associated with the latch plate, and a base having an

integral hood extending over said blank of metal whereby to protect the same and having 45 a guide for said blank of metal.

3. A door latch comprising a base plate formed with a curved hood constituting a protecting means and a gripping device, a latch plate pivoted to said base within said 50 hood and having keeper engaging means, said base being provided with guides contacting with said latch plate.

4. A door latch formed from a blank of flat metal having an attaching shank and a 55 flange which is bent outwardly to form a manipulating element, a keeper associated with the latch plate, and a combined hood and grip extending over said blank of metal and having one end terminating adjacent 60 said flange.

5. A door latch comprising a base having an integral transversely curved hood, the edge portions of said hood being provided with openings for the reception of fastening 65 devices, one end of said base being formed with a partly severed portion bent upon the base and in contact with the hood thereby forming a guide, said base being provided with a second partly severed portion defining 70 a guide, a latch plate having an extension fitted in said first named guide, the intermediate portion of said latch plate being adapted to be received within said second 75 named guide, the rear end portion of said latch plate being formed with an attaching shank and a manipulating flange bent outwardly at right angles to the latch plate, said manipulating flange being disposed adjacent one end of said hood, said first named 80 partly severed portion defining an opening, a keeper received within said opening, and a combined supporting and operating bolt connected to said shank and having a handle.

RICHARD G. WILLIS.
